UNITED STATES PATENT OFFICE.

CHARLES OSNER, OF WEST MIDDLETOWN, OHIO.

CHURN.

980,827.

Specification of Letters Patent. Patented Jan. 3, 1911.

Application filed April 18, 1910. Serial No. 556,231.

To all whom it may concern:

Be it known that I, CHARLES OSNER, a citizen of the United States, residing at West Middletown, in the county of Butler and State of Ohio, have invented certain new and useful Improvements in Churns; and I do declare the following to be a full, clear, and exact description of the invention, such as will enable others skilled in the art to which it appertains to make and use the same.

This invention relates to an improved mechanical movement especially adapted for use in operating barrel or tumbling churning.

The object of the invention is to provide simply constructed and efficient means for revolving the churn in one direction and the churn dasher in the other direction.

With the foregoing and other objects in view, the invention consists of certain novel features of construction, combination and arrangement of parts as will be more fully described and particularly pointed out in the appended claim.

In the accompanying drawings: Figure 1 is a side elevation partly in longitudinal vertical section of a churn showing this improved mechanism applied; Fig. 2 is an end elevation thereof; Fig. 3 is an enlarged detail section on the line 3—3 of Fig. 1.

In the embodiment illustrated a suitable churn support is shown preferably comprising the base plate 1 having standards 2 and 3 mounted thereon between which is revolvably mounted a barrel churn 4. The upper ends of these standards 2 and 3 are provided with recesses as 5 for removably supporting a shaft hereinafter described.

Mounted on one end of the barrel churn 4 and projecting therethrough is a hollow shaft 6 which is rigidly secured to the churn barrel 4 in any suitable manner being preferably provided near its inner end with a plate 7 cast integral therewith and arranged to bear against the outer face of the end of the churn 4 to afford an extended attaching surface therefor. This hollow shaft 6 is mounted in the recess 5 of the standard 2 and is provided on its outer end with a skeleton plate 8 preferably cast integral therewith and on which is mounted an annular internally toothed gear 9 of any desired or suitable size for engagement by a cog wheel hereinafter described whereby the churn body 4 is revolved. A bracket 10 is secured to the outer face of the standard 2

and the free end thereof is offset from said standard and provided with a suitable bearing for the reception of one end of a shaft 11 on which a cog wheel 13 is loosely mounted. This cog wheel 13 is preferably provided at its opposite ends with sleeves 14 and 15 for engagement with the shaft 11 to provide an extended bearing surface to cause said cog wheel to run true and whereby there will be less wear on said shaft and on the cog wheel sleeves.

The shaft 11 is preferably cast integral with a depending hanger member 16 the upper end of which is loosely mounted on a shaft 17 which extends through the hollow shaft 6. This shaft 17 is provided at its inner end within the churn body with a collar 18 which fits closely around the outer face of the shaft 6 and the free end of said shaft 17 is made angular and is preferably tapered to fit within a similarly shaped socket formed in one end of the dasher shaft 19 for a purpose to be described. The collar 18 fits closely over the end of the hollow shaft 6 to prevent all danger of the cream oozing through said shaft 6.

A cog wheel 20 provided with any desired number of teeth, preferably twenty-five, is fastened to the outer end of the shaft 17 and meshes with the cog wheel 13 by means of which the churn dasher is revolved.

After the cog wheel 13 has been placed on the shaft 11 a collar 21 is preferably forced on said shaft on its outer end to hold the cog wheel operatively in position and against which the end of the brace 10 rests. An angular portion 22 is formed near the outer end of this shaft 11 and is designed to fit in the slot 23 in the free end of the bracket 10 to hold said shaft firmly against turning. The outer extremity of this shaft 11 is threaded to receive a thumb nut 24 which is operable to hold the bracket end firmly against the collar 21. When the thumb nut 24 is loosened the shaft 11 may be disengaged from the bracket 10 when it is desired to remove the churn from its support.

The dasher shaft is provided with any suitable or desired number of blades as 26 which may be constructed in any desired form. The end of this shaft 19 opposite the end having the socket therein is provided with a casting 27 having a rounded aperture extending centrally therethrough into which a spindle 28 projects. This spindle 28 ex-

tends through a hollow stub shaft 29 secured to the outer face of the churn by any suitable means. This stub shaft 29 is designed to rest in the recess in the upper end of the 5 standard 3 and is provided on its free end with an operating crank handle 30 by means of which the churn barrel is rotated. The spindle 28 is provided on its free end with a thumb screw 31 which is removed when 10 it is desired to remove the dasher from the churn.

The gear 9 which is fixed to the casting 8 secured to one end of the churn barrel is provided with any desired number of teeth, 15 sixty-three being preferably used, and the cog-wheel 13 is preferably provided with twenty teeth any desired number, however, may be used.

In an operating mechanism constructed 20 as above described one revolution of the churn barrel 4 will cause the dasher to revolve three times in the opposite direction whereby the butter will be quickly churned.

From the foregoing description taken in 25 connection with the accompanying drawings, the construction and operation of the invention will be readily understood without requiring a more extended explanation.

Various changes in the form, proportion 30 and the minor details of construction may be resorted to without departing from the principle or sacrificing any of the advan-

tages of the invention as defined in the appended claim.

I claim as my invention:

A mechanism for operating the dasher shafts of churning and the like comprising standards with a hollow shaft having a plate at one end secured to the churn, said shaft also having a skeleton frame at its 40 other end provided with an internal gear wheel, a spindle inserted through said wheel, skeleton frame and hollow shaft and connected to the dasher shaft, said spindle having a cog wheel thereon and also provided with a hanger arranged between the gear wheel and skeleton frame, said hanger having a short shaft bent at right angles therewith and having thereon a pinion which meshes with said gear and cog wheels, a 45 supporting bracket connected to said short shaft, and means comprising a hollow shaft supported on the opposite standard and having a handle secured to one end and secured at the other end to the churn body whereby 50 the said body may be turned in one direction and the dasher in the opposite direction.

In testimony whereof I have hereunto set my hand in presence of two subscribing witnesses.

CHARLES OSNER.
